UNITED STATES PATENT OFFICE.

PHILIP D'HUC DRESSLER, OF LONDON, ENGLAND.

METHOD OF AND MEANS FOR SUPPORTING TILES, MORE ESPECIALLY WHILE SUBJECT TO HEAT TREATMENT.

1,368,219.

Specification of Letters Patent.

Patented Feb. 8, 1921.

Application filed August 25, 1916. Serial No. 116,914.

To all whom it may concern:

Be it known that I, PHILIP D'HUC DRESSLER, a subject of the King of Great Britain and Ireland, residing at London, England, 5 have invented Methods of and Means for Supporting Tiles, More Especially While Subject to Heat Treatment, of which the following is a specification.

This invention relates to the supporting

10 of tiles, more especially while subject to heat treatment, as for example when being gloss fired. For the latter and like purposes the method of supporting tiles in the vertical plane balanced upon two points of 15 contact in saggars, as nearly upright as is consistent with the stability of the tile, in contradistinction to other methods where the plane of each tile is horizontal, is recognized to be advantageous from the point of 20 view of reducing the proportion of the mass of the supporting material to that of the tiles supported. But even so, this method of supporting tiles, as aforesaid, in saggars, wastes much space, involves the heating use- 25 lessly of a mass of material which is still large in proportion to the mass of the tiles supported, and necessitates considerable expense in replacing broken saggars.

Now the object of the present invention 30 is to enable the space in ovens and muffles to be employed to greater advantage than has so far been possible and it is achieved by providing for the support of the tiles in the vertical plane in rows which can be 35 added to vertically without the necessity of using supplemental horizontal carrying bases, the whole forming a symmetrical and compact nest or stack in which the mass of supporting material in relation to the tile 40 mass is considerably reduced and space economized.

According to the invention the tiles are arranged to be stacked in pairs in the usual way, that is to say, back to back touching, 45 and face to face but slightly apart, in horizontal rows with their edges resting upon the keen arrises of rods or saddle backs of refractory materials, carried in horizontal rows limited only in number by considera- 50 tions of the cross sectional area of the oven or muffle to be used.

These rods may be carried by walls each made in one slab or of a number of slabs of material appropriately united together, al-

though in many cases it is thought that it 55 may be more convenient to constitute the walls of bricks which can be built up tier by tier as the work of supporting the tiles in rows proceeds. The rods or saddle backs 60 may be passed through holes in the walls, be adapted to rest on brackets carried by the walls, or be supported in both of these ways.

In the accompanying drawings, Figures 1 and 2 are elevations at right angles to each 65 other illustrating one way of carrying the invention into effect.

Fig. 3 is a detail view showing in side elevation a modification.

Fig. 4 is a part plan showing a further 70 modification.

According to the example shown in Figs. 1 and 2, a series of rods or saddle backs *a* of a double channel shape in cross section and made of refractory material are em- 75 ployed of a length necessitating a pair of end walls *b* and two intermediate walls *c* for their support, assuming that the platform *A* of a truck for use in a tunnel oven is to be loaded. Each wall *b* or *c* may be 80 built up of bricks *d*, *e* the majority *d* of which are of a length equal say to twice the height, although the length of each of the others *e* is say three times that of the height, rendered necessary for purposes of bonding. 85 Recesses *f* in the upper or under horizontal faces of these bricks, or in both of such faces, as in the example shown, serve to accommodate the rods or saddle backs *a* the majority of which latter support tiles *g* ar- 90 ranged at opposite sides thereof. In the longer bricks *e* any tendency of the rods *a* to spread, owing to the lateral thrust of the tiles *g* thereon, is resisted by the fact that recesses *f* for a pair of rods *a* are formed 95 therein, and the same tendency to spread which exists between the shorter bricks *d*, where each supports a single rod *a* is or may be resisted by interlocking means such as a key *h* adapted to enter recesses *h*¹ in the 100 companion faces of adjacent superposed bricks. Or as shown in Fig. 3, a lug *i* on one face of such a brick may be adapted to enter a recess *j* in the companion face of a brick in the next adjacent row.

As will be seen the tiles *g* are arranged 105 vertically in longitudinal rows, each row being supported by and between the keen

arises a^1 on two laterally adjacent rods a there being a number of such longitudinal rows arranged to form a vertical series of superposed horizontal sets of such rows.

5 In this example it has been assumed that only one size of square tile g is to be accommodated but it will be understood that by appropriate choice in the number of rod or saddle back supporting regions in the 10 various bricks composing the walls b, c and by suitably proportioning the height of the bricks and varying the number employed between rows of rods or saddle backs a , a wide range of sizes and shapes of tiles can be 15 economically dealt with.

Instead of using a number of long rods or saddle backs extending the width of the set of walls as in Figs. 1 and 2, a number of shorter ones each extending between adjacent pairs of walls may of course be used, 20 if desired, as shown in Fig. 4. In this case the shorter rods or saddle backs a are supported on brackets k on the walls b, c .

The bricks of which the walls are built up 25 may be dust pressed in steel dies, thus giving very regular and true shapes, facilitating assembly, and they may be more or less hollowed or recessed as shown at m in Fig. 2, or perforated as shown at n in Fig. 1, to 30 reduce their weight, while enabling a broad and stable base to be maintained.

What I claim is:—

1. The method of treating tiles, said method consisting in arranging the tiles 35 with their surfaces vertical to form a plurality of horizontal rows of tiles and supporting the rows of tiles in superposed parallel sets, the edges of the tiles being inclined to the horizontal and the horizontal rows of 40 tiles in one set being arranged in staggered relationship and parallel to those in an adjacent set.

2. The method of treating tiles, said method consisting in arranging the tiles, 45 with their surfaces vertical, in horizontal rows, supporting the rows of tiles in superposed parallel sets and in staggered relationship, the rows of tiles in one set extending into the angular spaces between the sides 50 of the rows of tiles in an adjacent set or sets and firing the tiles while supported in this position.

3. For supporting tiles in a vertical position, a plurality of rods spaced apart horizontally and vertically to form horizontal rows with the rods in one horizontal row out of vertical alinement with those in adjacent horizontal rows and means for supporting said rods in position.

60 4. For supporting tiles in a vertical position, a base piece, transverse walls disconnected from each other and spaced apart upon said base piece, each wall being built up of separate bricks or blocks placed freely 65 one upon the other and a plurality of hori-

zontal rods carried by and extending through said walls, said rods being spaced apart and arranged to form superposed horizontal sets of rods.

5. For supporting tiles in a vertical position, 70 a plurality of rods spaced apart in horizontal rows and transverse walls adapted at a number of successive levels to support said rows of rods one above the other to any desired extent, the rods in one horizontal row being out of vertical alinement 75 with those in adjacent horizontal rows.

6. For supporting tiles in a vertical position, 80 a plurality of rods spaced apart in horizontal rows and transverse walls adapted at a number of successive levels to support said rows of rods one above the other, the rods in one row being out of vertical alinement with those in adjacent rows and the walls being constituted of loose bricks 85 that can be built up tier by tier as the work of supporting the tiles on the rods proceeds.

7. For supporting tiles in a vertical position, 90 a plurality of rods, transverse walls built up of bricks resting freely one on the other and adapted to support said rods to form a vertical series of superposed horizontal rows and means for locking said bricks together sidewise to resist lateral 95 thrust on the rods due to the tiles supported thereby.

8. For supporting tiles in a vertical position, 100 an openwork structure comprising a base piece, transverse walls spaced apart and carried by said base piece and disconnected from each other and a plurality of rods or saddle backs of refractory material carried by said walls and arranged in superposed horizontal rows, each rod being formed with keen arrises adapted to engage 105 and support the edges of tiles arranged with their surfaces vertically, and said walls being constituted by loose bricks which can be built up tier by tier as the work of placing the rods or saddle backs in position and the 110 tiles thereon, proceeds.

9. For supporting tiles in a vertical position, 115 an openwork structure comprising a base piece, disconnected parallel walls carried by said base piece and formed with horizontal rows of apertures at different levels the apertures in one horizontal row being out of vertical alinement with those in adjacent rows, and a plurality of rods of refractory material extending through the 120 apertures in said walls and formed at their sides with keen arrises adapted to engage and support the edges of tiles placed vertically between laterally adjacent rods.

10. For supporting tiles in a vertical position, 125 an openwork structure comprising a platform, separate walls carried by said platform and composed of bricks resting freely one on the other and arranged in tiers, adjacent superposed bricks in each wall be- 130

ing shaped to form apertures between them, and a plurality of rods extending through the apertures in the walls and forming horizontal rows of rods, the rods in one horizontal row being out of vertical alinement with rods in adjacent horizontal rows.

Signed at New Castle, Lawrence County,

Pennsylvania, this twenty third day of August 1916.

PHILIP D'HUC DRESSLER.
